Patrick S. Holloran.

UNITED STATES PATENT OFFICE.

PATRICK S. HOLLORAN, OF WASHINGTON, DISTRICT OF COLUMBIA, ASSIGNOR
OF ONE-HALF TO THOMAS TRACY, OF SAME PLACE.

FAUCET AND BUSHING.

SPECIFICATION forming part of Letters Patent No. 242,322, dated May 31, 1881.

Application filed January 18, 1881. (No model.)

To all whom it may concern:

Be it known that I, PATRICK S. HOLLORAN, a citizen of the United States, residing in Washington, in the county of Washington and District of Columbia, have invented certain new and useful Improvements in Bushings and Faucets, of which the following is a specification.

The object of my invention is to provide a cheap and simple means for tapping beer and the like, in which there will be little or no liability of waste in the tapping, and no spring used in the faucet or bushing, as are at present used and found very objectionable.

The nature of my invention relates to improvements in faucets and bushings for barrels and the like; and the novelty consists in the construction and arrangement of parts, as will be hereinafter more fully set forth, and particularly pointed out in the claims.

In the accompanying drawings, forming a part of this application, Figure 1 is a representation of a perspective of the faucet with the plunger-arm removed. Fig. 2 is a perspective view of the bush. Fig. 3 is a sectional view of the perforated plunger-head. Fig. 4 is a perspective view of the solid plunger-head; and Fig. 5 is a longitudinal sectional view of the faucet and bush attached to a section of a portion of a barrel, with the plunger in a position to drive 30 the plug, also the position shown in dotted lines when the plug is driven.

Referring to the drawings, the letter A represents the barrel, B the bush, and C the faucet.

The faucet is constructed with the aperture 35 a, stuffing - box a', with the internal screw-threaded portion, b, a nozzle, c, plunger-bearings d, with an internally screw-threaded nut, d', and upon its opposite end a screw-threaded portion, e, with a flange, e'.

The letter D represents a plunger-rod having upon its outer end a square part, f, to which is attached a removable handle, f', when it is to be operated. Upon this plunger-rod, near its middle or lower end, is an enlarged portion, 45 g, which is externally screw-threaded to work in the threads of the nut on the plunger-bearings. The inner or lower end of the plunger-rod is also screw-threaded to receive the laterally and end perforated plunger-head E,

which forces the plug in by the rod, and also 50 serves as a strainer for the beer or other liquid; but when desired the solid plunger-head may be used, which is shown in Fig. 4 of the drawings.

h represents the bush-plug, which is also 55 shown in dotted lines in the act of being driven from the bush. h' is a screw-threaded cap, which is screwed in the head of the faucet, as shown, having an aperture for the passage of the plunger-rod.

The stuffing-box should be securely packed, which, with the cap screwed up, will prevent the escape of any of the contents of the barrel. The plunger-rod, which is braced in the faucet-head, and the screw-threaded nut in the bearings, is also provided with a lug or stop, which prevents the threaded portion of the said rod from being entirely removed from the nut.

The bush B has a flange, k, through which are screw-holes to firmly secure the same to a 70 barrel, a shoulder or faucet-seat, k', and roughened surface or diamond-shaped ragging, m, by which the plug is firmly held in place until forced in by the plunger. The bush is also screw-threaded at m' and n.

The operation of my invention is obvious. The bush B is intended to be permanently secured in the head of a barrel or other article to which my device is to be applied, the flange of which will bear against the article. The 80 faucet, with a leather or other suitable washer, o, placed upon it, as shown, is screwed into the bush until its end comes in contact with the flange of the bushing, or the two flanges tightly press against the said washer, thus 85 making a tight connection between the bush or barrel and the faucet. The barrel is then ready to be tapped, and by grasping the handle f' and screwing up the plunger-rod the tapping is effected and the liquid ready to be 90 drawn through the faucet and the spigot H on the nozzle.

Although my invention is not revolutionary in its character or scope, I believe it is of sufficient novelty to deserve protection.

Having thus fully described my invention, what I claim as new, and desire to secure by Letters Patent of the United States, is—

1. As an improvement in bushings for barrels, the bush B, having the internal ragging, m, as shown, to hold the plug therein, substantially as specified.
- 5 2. As an improvement in faucets, the faucet C, constructed as described, having the plunger-rod D, provided at its inner end with the

perforated head E, adapted to displace the plug in the bushing and partially fill the opening in the same, substantially as specified.

PATRICK S. HOLLORAN.
